CLAIM

The ornamental design for an earphones with charging case, as shown and described.

DESCRIPTION

FIG. 1 is a front perspective view of an earphones with charging case, showing my new design;

FIG. 2 is another front perspective view of the earphones with charging case, shown in an open state.

FIG. 3 is a front view of the earphones with charging case, shown in a closed state;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view of a left-side earphone of the earphones with charging case, shown separately to show aspects of the design that are not visible when combined;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a rear perspective view of a right-side earphone of the earphones with charging case, shown separately to show aspects of the design that are not visible when combined;

FIG. 17 is a front view thereof;

FIG. 18 is a rear view thereof;

FIG. 19 is a left side view thereof;

FIG. 20 is a right side view thereof;

FIG. 21 is a top view thereof; and,

FIG. 22 is a bottom view thereof.

(Continued)

The broken lines in the drawings illustrate the portions of the earphones with charging case that form no part of the claimed design.
